UNITED STATES PATENT OFFICE

107,378

DESIGN FOR A HAND VANITY MIRROR

William La Hodny, Buffalo, N. Y.

Application May 10, 1937, Serial No. 69,253

Term of patent 3½ years

To all whom it may concern:

Be it known that I, William La Hodny, a citizen of the United States and residing at Buffalo, in the county of Erie and State of New York, have invented a new, original, and ornamental Design for a Hand Vanity Mirror, of which the following is a specification, reference being had to the accompanying drawing forming part thereof.

In said drawing:

side of the hand vanity mirror showing my new design.

Figure 2 is a perspective view of the reverse side of the hand vanity mirror.

The characteristic feature of my design resides in the handle portion.

I claim:

The ornamental design for a hand vanity mirror, as shown and described.

WILLIAM LA HODNY.
